(57) **CLAIM**

The ornamental design for a rifle recoil pad, as shown and described.

DESCRIPTION

FIG. 1 is a front perspective view of a rifle recoil pad;

FIG. 2 is a rear perspective view of the rifle recoil pad;

FIG. 3 is front elevational view thereof;

FIG. 4 is a rear elevational view thereof;

FIG. 5 is left side elevational view thereof;

FIG. 6 is a right side elevational view thereof;

FIG. 7 is a top view thereof; and,

FIG. 8 is a bottom view thereof.

The broken lines depict environmental structure for illustrative purposes only and form no part of the claimed design.

1 Claim, 5 Drawing Sheets
